UNITED STATES PATENT OFFICE.

GEORGE P. BILLINGS, OF BAR HARBOR, MAINE.

MACHINE FOR FINISHING AND SMOOTHING FLOORS.

No. 873,207.

Specification of Letters Patent.

Patented Dec. 10, 1907.

Application filed May 22, 1907. Serial No. 375,092.

To all whom it may concern:

Be it known that I, GEORGE P. BILLINGS, a citizen of the United States, residing at Bar Harbor, in the county of Hancock and State of Maine, have invented a new and useful Machine for Finishing and Smoothing Floors, of which the following is a specification.

This invention relates to machines for 10 finishing or smoothing floors and has for its object to simplify and improve the construction of devices of this character.

Another object is to dispose the grinding or finishing heads at points where they are at 15 all times in view of the operator so that the progress and character of the work performed by the machine can be seen at all times.

Another object is to utilize mechanism 20 which will keep the floor clean of dust during the smoothing operation, the collection of the dust being facilitated by the novel disposition and arrangement of the finishing or smoothing heads.

25 A still further object is to provide a machine of this character which can be readily tilted so as to lift the grinding or smoothing heads out of contact with the floor and which will remain in tilted position as long as desired.

With these and other objects in view the invention consists of certain novel features of construction and combinations of parts which will be hereinafter more fully described 35 and pointed out in the claims.

In the accompanying drawings is shown the preferred form of the invention.

In said drawings: Figure 1 is a perspective view of the machine; and Fig. 2 is a section 40 through a modified form of grinding head.

Referring to the figures by characters of reference, 1 is a truck frame provided adjacent the center of its sides with supporting rollers 2, while at the rear end of the frame 45 are small auxiliary rollers 3 designed to contact with the floor only when the truck frame is tilted out of operative position. Extending upward from the truck frame are standards 4 which support a top frame 5 suitably 50 braced and having bars 6 secured to the sides thereof and inclined therefrom, said bars being connected at their outer ends by a cross strip 7 constituting a handle. Boxes 8 and 9 are secured to the front ends of the truck 55 frame and the top frame respectively and journaled therein is a pair of upright shafts

10 provided with collars 11 which bear against the lower ends of the boxes 9 and the upper ends of the boxes 8 respectively so as to prevent longitudinal movement of the 60 shafts. Each shaft has a pulley 12 thereon on which is mounted a belt 13. Both belts receive motion from pulleys 14 located at the ends of a shaft 15 driven by an electric motor 16. This motor is mounted upon the 65 rear end portion of the truck frame and is provided with a suitable controller 17 mounted upon the top frame 5. The controller is designed to be electrically connected to a source of electricity in any suitable 70 manner and a switch 18 may be provided for cutting off the current from the machine. A receiver 19 is carried by the truck frame and communicates with a fan 20 through a tube. 21. The fan is designed to be driven by a 75 belt 22 receiving motion from the motor 16.

The lower end of the shaft 10 is provided with a head preferably in the form of a disk 23 having an upstanding sleeve 24 designed to be secured to the shaft in any preferred 80 manner as by means of a set screw 24'. The lower face of this disk may be covered with sand or emery paper which can be secured thereto in any suitable manner, as by means of a ring 25. If preferred, however, a head 85 such as shown in Fig. 2 may be employed and this head is in the form of a metal disk 26 having openings 27 punched therethrough forming projecting points 28 constituting a rasp. A sleeve 29 extends upward from the center of the disk and is designed to be fastened upon either shaft 10. 90

It will be noted that the grinding heads are located at the front end of the machine where they are in full view of the operator 95 grasping the handle 7. The entire device is balanced upon the rollers 2 so that by tilting the truck frame 1 backward the rollers 3 will come in contact with the ground and the device will remain supported with the heads 23 100 out of contact with the floor. By swinging the front end of the truck frame downward the heads 23 will be brought in contact with the floor and will be held in such position by the weight of the machine. The belts 13 105 are so disposed that when the motor 16 is operating the two shafts 10 will be rotated in the directions indicated by the arrows in Fig. 1. It is designed to rotate these shafts very rapidly and it is of course apparent 110 that the grinding heads will quickly smooth the surface thereunder and as they rotate in

the direction indicated it is apparent that the dust produced will be thrown backward under the frame where it will be taken up by the suction established by fan 20. The dust 5 will therefore be brought into the receptacle 19. As the heads are disposed directly under the handle 7 they are at all times in full view of the operator who can readily determine when a sufficient grinding action has 10 been produced at a certain point. Whenever it is desired to stop the grinding operation it is merely necessary to swing the front end of the machine upward so that the rollers 3 will come in contact with the floor and 15 while the motor and the parts driven thereby will continue to operate the heads 23 will be supported out of contact with the floor.

The heads shown in Fig. 1 are particularly designed to finish smooth surfaces but whenever 20 it is desired to surface warped edges of floor boards or to remove shellac and the like heads such as shown in Fig. 2 are preferably substituted for those disclosed in Fig. 1. Also if it is desired to smooth off knots or 25 other projecting portions upon the surface of the floor heads utilizing knives can be substituted for those described.

It is of course to be understood that this machine is only designed to be used where 30 electric wires are installed and it is the purpose to connect it to a source of electricity by a long flexible wire which is of sufficient length to permit considerable movement of the machine over the floor.

It will be obvious that the machine herein 35 described can be effectively used for smoothing and polishing mosaic, tile, marble or other similar floors in which event disks of emery or other suitable material may be substituted for the heads 23 and 26. As it 40 would be desirable for such disks to rotate slower than where wooden floors are being finished larger pulleys are arranged upon the shaft 10 so that the speed of rotation will be diminished.

45

What is claimed is:

The combination with a portable tiltable frame; of shafts journaled upon one end of the frame, floor finishing devices revoluble therewith and disposed to contact with the 50 surface thereunder and support the frame when oscillated in one direction, means for simultaneously rotating the shafts in opposite directions and at the same speed, a receiver carried by the frame and in rear of the 55 shafts, said finishing devices being disposed to throw loosened material beneath the receiver, a suction device for establishing an air current upward through the receiver, and a handle above said floor finishing devices 60 and extending beyond the end of the frame.

In testimony that I claim the foregoing as my own, I have hereto affixed my signature in the presence of two witnesses.

GEORGE P. BILLINGS.
